PULL

John R. Morgan, Wheeling, Ill., assignor to Amerock Corporation, Rockford, Ill., a corporation of Illinois

Filed May 14, 1963, Ser. No. 74,872

Term of patent 14 years

(Cl. D10—8)

FIGURE 1 is a front elevational view of a pull embodying my new design.

FIG. 2 is a top view of the pull.

FIG. 3 is a side elevational view of the pull as viewed from the left in FIG. 1.

FIG. 4 is a side elevational view of the pull as viewed from the right in FIG. 1.

FIG. 5 is a back view of the pull.

FIG. 6 is a sectional view taken along the line 6—6 in FIG. 3.

FIG. 7 is a sectional view taken along the line 7—7 in FIG. 1.

FIG. 8 is a sectional view taken along the line 8—8 in FIG. 4.

I claim:

The ornamental design for a pull, substantially as shown.
